W. G. CHAUSSÉ,
SAFETY DEVICE FOR GAS GENERATING AND HEATING APPARATUS,
APPLICATION FILED AUG. 8, 1919.

1,423,080.

Patented July 18, 1922.

2 SHEETS—SHEET 1.

UNITED STATES PATENT OFFICE.

WILFRID G. CHAUSSÉ, OF DETROIT, MICHIGAN.

SAFETY DEVICE FOR GAS GENERATING AND HEATING APPARATUS.

1,423,080.

Specification of Letters Patent.

Patented July 18, 1922.

Application filed August 8, 1919. Serial No. 316,081.

To all whom it may concern:

Be it known that I, WILFRID G. CHAUSSÉ, a citizen of the United States of America, residing at Detroit, in the county of Wayne

5 and State of Michigan, have invented certain new and useful Improvements in Safety Devices for Gas Generating and Heating Apparatus, of which the following is a specification, reference being had therein to

10 the accompanying drawings.

This invention relates to a burner and a gas generating apparatus adapted to supply gas to the burner, the gas being generated from kerosene or a suitable fuel 15 which is maintained in proximity to the burner so that the burner may be utilized for converting the fuel into a gas or vapor form.

My invention aims to provide an apparatus 20 of the above type wherein the supply of fuel is maintained under pressure so that it will be forcibly fed to a generator subjected to the action of heat from the burner, said generator also serving as means for disseminating heat, so that the generator 25 may be used as a heating medium in a stove or other structure. When using a volatile or combustible fuel, under pressure, there is a degree of danger which is materially increased when the gas generating apparatus forms part of a car or vehicle equipment.

For instance it is the present practice to provide cars and other vehicles with a heating apparatus wherein the heat is the result 30 of a generated gas or liquid fuel, and when a wreck occurs or the car or vehicle is set on fire, there is a possibility of escaping gas or fuel being ignited and causing further damage, if not the loss of life due

35 to explosion. It is therefore essential that safety devices be used and my invention includes a device for this purpose and in case of a fire or a collision, either of which would injure or wreck the heating apparatus, the 40 gas generator is immediately rendered inoperative and the supply of fuel shut off so that it cannot escape.

My invention is further characterized by a heating apparatus that is compact, inexpensive to operate, easy to control, and highly efficient for the purposes for which

it is intended. The mechanical construction and arrangement of parts entering into the invention will be hereinafter more fully considered and then claimed.

Reference will now be had to the drawings, wherein

Figure 1 is a front elevation of the gas generating apparatus in connection with a stove;

Fig. 2 is an enlarged detail sectional view of a safety device forming part of the apparatus;

Fig. 3 is an enlarged detail view of a portion of the gas generator, partly in section;

Fig. 4 is a vertical sectional view, partly in elevation, of another form of apparatus;

Fig. 5 is a side elevation of a stove equipped with the apparatus, and

Fig. 6 is an elevation, partly in section, of a further form of the apparatus.

The gas generator comprises a central hollow body 1 having a plurality of radially disposed hollow arms 2 communicating with said body and said body and its arms may be conveniently made of tubing. In the body and its arms is placed metallic wool 3 or any non-combustible heat absorbing and baffling material through which fuel, as kerosene, may be forced, disintegrated, baffled and heated to that extent as to be converted into gas.

The lower end of the hollow body 1 is provided with a reducing connection 4 with which communicates a fuel supply pipe 5 having a shut off valve 6 and said fuel supply pipe communicates with the bottom of a fuel tank 7 adapted to contain kerosene or other fuel.

The upper end of the hollow body 1 is connected by a pipe 8 to a burner 9 in proximity to the generator, so that the flames from the burner will be directed against the generator and heat the arms and body thereof, causing the fuel passing through the generator to be converted into gas and burned at the burner.

To force the fuel into the generator, under pressure, air or a motive fluid is employed, the air being stored, under pressure, in a tank or reservoir 10. The tank or reservoir 10 has a pipe 11 communicating with a two-

way valve 12, which is normally open. The pipe 11 may be provided with a pressure gauge 13 and a shut off valve 14.

The two-way valve 12 is connected by a 5 pipe 15 to a T connection 16 and said T connection communicates with the top of the fuel tank 7 through the medium of a pipe 17. Another pipe 18 establishes communication between the T connection 16 10 and a two-way valve 19, said two-way valve having an exhaust pipe 20 open to the atmosphere. The pipes 15 and 18 are placed in alignment so that the two-way valves 12 and 19 will be superposed and these valves 15 have the plugs thereof provided with weighted stems or levers 21, and these stems or levers have ends thereof connected by a safety device which maintains the valve 12 open and the valve 19 closed against any 20 action by the weights 22 on the stems or levers.

The safety device comprises connectors 23 provided with fuses 24 and said fuses are connected to the terminals 25 of a fragile 25 member 26, said member being preferably in the form of a glass tube having a collar 27 supporting a weight or disrupting member 28, which is mounted on the tube and has sharp edges 29 against the tube so that 30 the tube will be broken by any jarring of the weight or member 28.

Below the gas generator is a basin 30 in which the small quantity of kerosene may be placed and ignited so as to heat the gas 35 generator preparatory to starting the apparatus. Assuming that the generator has an initial heat, the valves 14 and 6 are open, and the air from the tank 10 passes through the pipe 11, valve 12, pipe 15, connection 40 16 and pipe 17 into the fuel tank, on top of the fuel therein, causing the fuel to be forced upwardly in the pipe 5 and into the gas generator, where it is converted into gas to burn at the burner 9.

45 Should an accident occur, for instance by fire, the fuses 24 will melt and release the ends of the valve stems or levers 21, permitting the normally open valve 12 to close and the normally closed valve 19 to open.

50 The supply of air is therefore shut off from the fuel tank and such air that remains in the fuel tank is permitted to exhaust through the valve 19 and the pipe 20. It is therefore obvious that the flow of fuel to the gas 55 generator will be discontinued and result in a cessation in the operation of the apparatus.

As shown in Fig. 1, the gas generator may be conveniently located in a stove structure 60 31 and the safety device located in a compartment 32 of the stove structure or at some point where the fuses are protected from the heat of the stove.

Should an accident occur that would wreck 65 the stove structure, then the sudden vibra-

tion causes the member 28 to disrupt the tube 26, releasing the valve stems or levers 29 and causing a cessation in the operation of the apparatus as pointed out in the case of fire.

70 Considering the form shown in Figs. 4 and 5, a stove structure 33 has a side framework 34 supporting a pipe 35 establishing communication between valve bodies 36 and 37, and in said valve bodies are valves 38 75 and 39 respectively, said valves being connected by a valve rod 40 provided with a turnbuckle 41 so that the longitudinal dimension of the valve rod may be increased or decreased to insure proper seating of the 80 valves at the ends thereof. The valve rod 40 extends through suitable stuffing boxes 42 of the valve bodies 36 and 37 and connected to said valve rod, intermediate the ends thereof, is a weighted lever 43 which has the 85 inner end thereof pivotally connected, as at 44, to the pipe 35 and the outer end of said lever has a weight 45.

The valve body 36 is in communication with an air supply pipe 46 and the valve 90 body 37 with an exhaust pipe 47 and an outlet pipe 48 adapted to communicate with a fuel tank.

95 On the outlet pipe 48 is a socket 49 for a spring supported yieldable cup 50 which supports a safety device 51 somewhat similar to the safety device previously described and shown in Fig. 2, with the exception that the safety device 51 has a fuse 52 connecting said safety device to the lever 43. Then 100 again, the weight or disrupting member of the safety device is connected to the outlet pipe 48 by a flexible member 53, as a chain, so that said weight will at all times be convenient for another installation of a safety 105 device.

110 As in the form previously described, one of the valves is always open, and the other closed, so that air may pass from the air tank to the fuel tank and force fuel through the generator. When the safety device 51 releases the weighted lever 43, said lever immediately shifts the valve rod 40, closing the valve 38 and opening the valve 39 so that any air within the fuel tank may exhaust to the atmosphere.

115 Another form of my invention has been illustrated in Fig. 6, and this form obviates the necessity of using two valve bodies and two weighted levers. A single four-way 120 valve 54 is employed, said valve communicating with an air tank 55, the top of a fuel tank 56, the bottom of said tank, and also the gas generator so that when the plug 57 in the four-way valve is properly positioned 125 the air from the tank 55 may pass into the tank 56 and force the fuel out of said tank upwardly and through the four-way valve to the gas generator. The plug 57 of the four-way valve has a weighted lever 58 associated 130

with a safety device 59, similar to the safety device 51. In case of a fire or collision the lever 58 is released and the plug 57 is partially rotated, the rotation of said plug being limited by a stop 60 of the valve, whereby the plug will shut off the supply of air to the fuel tank and also the supply of fuel to the valve, thus preventing the escape of air or fuel during a cessation in the operation 10 of the apparatus.

My invention is not necessarily confined to use in cars or vehicles but may be used as a heating apparatus for general purposes, and while in the drawings there are illustrated the preferred embodiments of my invention, it is to be understood that the structural elements are susceptible to such variations and modifications as fall within the scope of the appended claims.

20 What I claim is:—

1. The combination of a gas generator, a fuel supply tank communicating therewith, a supply of air under pressure communicating with said fuel supply tank and adapted 25 to force fuel to said generator, a burner communicating with said generator and adapted to receive gas therefrom and heat

said generator, and valvular means controlling the supply of air to said fuel supply tank and adapted to automatically shut off the supply of air to said fuel tank and release the pressure of air in said fuel tank.

2. A heating apparatus supplied with fuel from a tank having fuel therein under pressure by air from another tank, and automatically operated means adapted to shut off the supply of fuel and open the fuel tank to the atmosphere so as to reduce the pressure therein.

3. In a forced feed fuel supply for a burner utilizing fuel from a tank communicating with a supply of air under pressure adapted to force the fuel to the burner; valvular means automatically actuated to close the communication between said tanks 45 and open said fuel tank to the atmosphere so that the pressure on the fuel therein is reduced.

In testimony whereof I affix my signature in the presence of two subscribing witnesses. 50

WILFRID G. CHAUSSE.
